FRANCE.

METHOD OF PREPARING SCREENS FOR COLOR PHOTOGRAPHY.

995,405.

Specification of Letters Patent. Patented June 13, 1911.

Original application filed January 2, 1907, Serial No. 350,334. Divided and this application filed June 22, 1911. Serial No. 568,276.

To all whom it may concern:

Be it known that we, LOUIS DUCOS DU HAURON and RAYMOND DE BERCEGOL, both citizens of the Republic of France, and residents of Joinville-le-Pont, Seine, Republic of France, have invented a new and Improved Method of Preparing Screens for Color Photography, of which the following is a full, clear, and exact description, this 10 being a division of the application filed by us on January 2, 1907, Serial No. 350,334, for the manufacture of screens for use in color photography.

Our invention relates to the manufacture 15 of polychromatic screens for use in color photography, under such conditions that the pictures or portions thereof may be multiplied.

We seek to cover a transparent or translucent surface, of glass, celluloid, paper or the like, with a very large number of exceedingly small rectangular figures, such as bands, rectangles, lozenge-shaped figures, etc., having three distinct colors placed 25 closely together without leaving any interval, and each of these colors covering theoretically one-third of the surface. By doing this in a skilful manner, the process may be carried out rapidly, economically and in 30 every manner suitable for industrial conditions.

Two things are essential in carrying out our process, to wit: First, the automatic placing or positioning of the colors relatively to each other, by taking advantage of the fact that colors dissolved in liquids of different character do not readily mix—that is to say, colors mixed with greasy substances and colors dissolved in water or in alcohol, 40 do not mix easily; second, the application of these colors thus treated, to parallel lines by means of a ruling machine.

Several forms of the invention are herein illustrated and described in order to render 45 the process easily understood.

Reference is to be had to the accompanying drawings forming a part of this specification, in which similar characters of reference indicate corresponding parts in all the 50 figures.

Figure 1 shows on an enlarged scale a portion of the screens obtained by the process; Figs. 2, 3 and 4 show variations; Fig. 5 is a

side view of a machine for tracing the lines; Fig. 6 is a plan view; Fig. 7 is an end view; 55 Fig. 8 is a section on the line of the cutting tool.

We select a hard plane surface, preferably one of copper, zinc or lithographic stone, and upon this surface lines are drawn by 60 means of a machine, these lines being parallel with each other and separated by intervals. This being done, the surface is partly in relief and partly in intaglio. The parts in relief are next coated, or the intaglio portions (that is, the holes or grooves) are covered with a greasy coloring material—for instance, green printing ink. By means of pressure the series of lines is now reproduced upon a sheet of gelatin, or upon some 70 other appropriate surface adapted to receive an impression. This is now dried and after drying a tracing of another color may be formed. This color, for instance, may be orange, and is so arranged that the lines 75 cross those first made. The bare intervals are next colored by applying to the whole surface of the sheet a third color, blue violet, dissolved in water, and to which the greasy colors are impermeable.

The screen thus made possesses, as shown upon a large scale in Fig. 1, a large number of comparatively small figures or designs, which may have the form of squares, rectangles, or lozenges, accordingly as the series 85 of lines are perpendicular or oblique.

At *v* is shown the green color, at *r* the orange color, and at *b* the blue color. At the crossings of the various lines appear small patches of black or dark color *n* which present a very slight disadvantage, to wit: that of slightly darkening the entire screen. The black or dark element *n* may be avoided, however, by operating as follows: Upon a surface, such as gelatin capable of dissolving water color, we first draw a series of lines, substantially as heretofore described, by means of a greasy ink of blue violet color, and then a yellow water color is applied over the entire surface. The material thus 95 applied does not adhere to the greasy lines and only fills the intaglio portions comprised between these lines. A second series of lines is then drawn by means of a greasy ink of light blue color, care being taken to 100 cross the lines just mentioned. The light

blue lines in being superposed upon the yellow lines will produce green colors, and in being superposed upon the blue violet color will have little or no effect beyond slightly increasing the intensity of this color. These three operations produce on the gelatin surface blue violet lines and green rectangles, resulting from the superposition of the yellow lines on the light blue lines; and since the lines and the squares are produced by inks having greasy solvents, these lines are not attacked by the other color whose solvent is water. Finally, over the entire surface is applied a layer of red water color which in mixing with the yellow gives the orange red color.

Our process may be used in connection with glass surfaces as follows: Upon a sheet of glass we spread gelatin holding in suspension very fine grains, such as those of starch. The sheet is then dried, the result being a slightly grainy surface holding the greasy ink and avoiding blurring, as well as enabling us to obtain, under the press, series of lines having remarkable clearness. To avoid breaking the glass and also to render the prints homogeneous, the plate produced by the ruling machine must be absolutely smooth, or better still, made up of a soft material, such as ebonite, celluloid, or very thin metal, placed on a sheet of india-rubber or other flexible material, so as to exactly compensate, when submitted to pressure, the unevenness of the glass. The two colors in greasy inks are applied as above described and the gelatin is caused to absorb the water color which now fills the hollows and completes the trichromatic screen. If it happens that the third color is blue violet, there can still be added to the gelatin, before it spreads over the transparent support, starch, which in this case must be dissolved. The last operation consists in causing to act in the greasy hollows upon the intaglio portions, a solution of iodin which causes the starch to become of a blue violet color.

The present process can also be carried out as follows: 1. On a substance permeable to water a first set of greasy lines which may be colorless, is drawn; 2. Over the whole surface an aqueous color containing tannin, alum, or any other substance susceptible of making the gelatin impermeable to color solutions similar to that first applied, is applied; 3. By means of a dissolvent, such as turpentine or mineral essence, etc., the greasy lines are destroyed in order that only the aqueous color lines may remain. 4. A second set of greasy lines crossing the preceding lines, and which may be colorless, as the first ones, is drawn; 5. A second water color, likewise containing tannin, alum, etc., is applied over the whole surface; 6. As previously done, said second set of greasy

lines is destroyed; 7. Finally, the third water color is applied over the whole surface.

If there be mixed with the water color a suitable proportion of material having the property of tanning gelatin and filling the pores thereof—in other words, if we add to the water color alum, tannin, alcohol, aldehyde, or the like—the space occupied by this color will be thereby rendered impermeable. A second aqueous color is now applied by the same means, and after drying, the third color, which is likewise a water color and though spread over the whole surface, will adhere only to the intaglio portions left.

Instead of obtaining the lines by transfer, they may be drawn directly upon the screen. In this case the procedure is as follows: A sheet of glass or celluloid is first covered with a material which is permeable to water and which is colored, for example, red. Then by means of a plane or circular ruling machine we draw small parallel grooves which are separated by intervals approximating their width. The sheet thus prepared is dipped for a few seconds into a water color—green, for example—which impregnates the gelatin throughout wherever it has been exposed, leaving unaffected the parts covered with varnish and merely dyeing superficially the layer of gelatin. The surface is now clean. It constitutes, in effect, a screen composed of green and red orange bands arranged side by side relatively to each other and capable of producing, by the two-color process, beautifully colored photographs.

The third color is distributed as follows: There is spread over a surface provided with two series of bands or lines, a second varnish which is impermeable to water, is colorless, and is designed to serve solely as a protector; we then hollow out fresh tracks which are a little deeper than those above referred to, in such a manner as to expose the lower layer of gelatin which the first bath did not have time to reach. These tracks intersect the first mentioned ones either perpendicularly or obliquely and should be separated by spaces equal to twice their own width. The sheet is then dipped for a few seconds into a blue-violet water-color bath and a three-color screen is produced. It has an extremely large number of small green and red-orange rectangles, *v*, *v*, respectively, intersected by blue-violet lines *b*, as shown in Fig. 2 of the accompanying drawings. These small figures will be lozenge-shaped if the second series of bands or tracks has been drawn obliquely, as shown in Fig. 3 of the drawings. The colors may obviously be arranged in any desired order.

We may also take a transparent sheet covered with a thick layer of gelatin which is superficially colored green for example on

which is spread a varnish impermeable to water. After having drawn the first series of bands or tracks, the sheet is dipped into a second water-color bath as for instance, 5 red-orange color, then a colorless protective varnish is spread thereon, the second deeper series of bands or tracks is drawn and finally the sheet is dipped into a third water-color bath, as, for instance, blue-violet. Celluloid which is superficially colored green, for 10 example, may also be employed; this is covered with colorless gelatin and the first series of bands or tracks is drawn sufficiently deep for them to expose the colorless celluloid. 15 The sheet is then colored with a pigment dissolved in acetone, amyl acetate or any other liquid which will bite into or penetrate the celluloid. There is then spread over the whole surface a second layer of gelatin, then 20 the second deeper series of bands or tracks is drawn, and finally there is spread over the whole surface a third color having a base of acetone or amyl acetate.

The gelatin having protected the parts of 25 the surface not acted upon by the chisel or tool of the ruling machine, and after having freed the celluloid from the gelatin, there will be produced a screen which is capable of resisting water and a large number of other 30 liquids.

In using celluloid the procedure is as follows: The sheet of celluloid is covered with a thin layer of gelatin which is colored by means of a water color, then the first series 35 of bands or tracks is drawn through the gelatin; the sheet is colored with a second color having amyl acetate or acetone for its base, which only acts on the exposed parts of the celluloid, the whole is then covered 40 with a second layer of colorless gelatin; the second series of bands or tracks which are deeper than the former ones is drawn and a third color of the same nature as the second is spread over the sheet.

45 In all the above cases, the first series of bands or tracks can be drawn in such a manner that the interval which separates them shall be equal to twice their width, as shown in Fig. 4 of the drawings. Then, after soaking and varnishing, similar bands or tracks 50 are drawn extending nearly to the middle of the space which is afterward soaked in the third color. In this manner, the screen is formed solely by bands which are parallel to 55 each other, but this process has the disadvantage of only overcoming part of the difficulties of registration, while the method in which the lines cross overcomes them entirely. Thus, the second series of bands or 60 tracks can be hollowed to the same extent as the first; in this case, two colors are superposed and form at the point at which the series of lines cross each other as hereinbefore specified and as shown in Fig. 1 small

squares n which are black or have a dark 65 color.

In most cases, as above specified the gelatin may be replaced by collodion or by any other material which may be easily spread in a thin layer and is capable of absorbing 70 colors having water, alcohol, etc., as their bases.

For drawing lines, the ruling machines may be used in which gravers or chisels are employed, and by mounting preferably on 75 these machines a plurality of chisels or gravers arranged so as to form a number of lines at a time. Also, in order to produce film-like screens, we can use a circular ruling machine similar to that shown by way of example in Figs. 5, 6, 7 and 8. This machine consists of a movable cylinder 1 around which the sheet is rolled, and of a chisel or cutting tool 2 which is fed along by a leading screw 3, and toothed wheels 4 and 5, of 80 which the wheel 5 is attached to the shaft of the cylinder 1. In order that the eye may not be able to distinguish separately the small colored divisions, their dimensions should be made as small as possible, and thus 85 a surface will be obtained which will appear homogeneous and whitish by transmittent light.

In order to allow the use of rotary pressure, the series of lines can be drawn on 90 cylinders.

In use, the screen produced by one of the methods described above, and protected by an impermeable varnish, is covered with an emulsion which is sensitive to colors, and 100 is placed in the plate or film-carrier or frame of any suitable photographic apparatus, the emulsion being turned toward the inner face of the said carrier or frame in such a manner that the rays of light pass through the 105 screen before reaching the said emulsion. A view will be taken in the ordinary manner and developed, then the negative so obtained will be converted into a positive and after fixing we will have a photograph having all 110 the natural colors; at the same time, we can employ the following process when it appears to be more advantageous by reason of its permitting the production of a large 115 number of prints.

Instead of spreading the emulsion on the screen itself, there is placed in the carrier or frame, in the ordinary manner, a sensitized plate to which the screen is applied, by putting the colored surface of the latter against 120 the emulsion on the plate. The view is taken, then the plate is developed after having been separated from the screen. The selectively acted upon negative thus produced, when fixed, will enable an indefinite 125 number of black positives to be obtained which, when suitably placed against similar screens will immediately exhibit by trans-

mitted light all the colorations of the model. Theoretically this adaptation or fitting of the screen to the positive, should be made in such a manner that each of the small colored figures should coincide with the point of the image which it has selected, but since these thousands of figures or devices are similar to each other, are of equal dimensions and are symmetrically distributed over the whole surface of the screen, by reason of the regularity of the work done by the ruling machine, the registration may easily take place with an infinity of positions.

15 The transparent support of the improved screens serving for the selection may be colored slightly yellow so as to moderate the activity of the blue-violet rays. The successive crossing of the two series of lines thus assists the complications of registration in the manufacture of the screens. Moreover, the successive soakings each time exactly filling up the spaces produced, it follows that all the small color-compartments 20 are automatically juxtaposed without any space being left between them, a condition which is especially advantageous in the production of phototypes in which the selective effect is produced by light-filtration. The perfect regularity of the screens enables them to be applied to any positive produced by a similar screen, and consequently to enable the prints to be multiplied indefinitely.

35 Having thus described our invention, we claim as new and desire to secure by Letters Patent:

1. The method herein described of making screens with polychromatic divisions, which 40 consists in first impressing upon a transparent support definite spaced figures, next coloring the intervals not covered by the figures by means of a color solution that will enter

the support in the parts unprotected by the printing substance but will not affect this 45 substance, next rendering impermeable to color solutions the parts of the support already colored, then destroying the printing substance impression and finally coloring the permeable intervals by means of a 50 color that will enter the support.

2. The method herein described of making screens with polychromatic divisions for color photography, which consists in first impressing upon a transparent support a 5 first group of lines in a fatty printing substance, next applying on the whole surface of the support a color solution capable of entering the support in the parts unprotected by the fatty printing substance, but 6 non-miscible with said substance, next rendering impermeable to color solutions the parts of the support already colored, then destroying the fatty lines by means of a suitable solvent, then impressing a second 6 group of fatty lines crossing the first group, then applying a second color capable of entering the permeable parts of the support unprotected by the fatty printing substance, said second color being non-miscible with 70 said substance, then rendering impermeable to color solutions the new colored parts of the support, then destroying the second group of fatty lines by dissolving the same, and finally applying a third color capable of 75 entering the permeable unprotected parts of the support.

In testimony whereof we have signed our names to this specification in the presence of two subscribing witnesses.
